UNITED STATES PATENT OFFICE.

HENRY RUPPEL, OF CLEVELAND, OHIO, ASSIGNOR TO AMERICAN STOVE COMPANY, OF ST. LOUIS, MISSOURI, A CORPORATION OF NEW JERSEY.

PERFORATED COMBUSTION-SECTION FOR BLUE-FLAME STOVES.

1,333,577.

Specification of Letters Patent.

Patented Mar. 9, 1920.

Application filed April 25, 1919. Serial No. 292,680.

To all whom it may concern:

Be it known that I, HENRY RUPPEL, a citizen of the United States, residing at Cleveland, in the county of Cuyahoga and

5 State of Ohio, have invented certain new and useful Improvements in Perforated Combustion-Sections for Blue-Flame Stoves, of which the following is a specification, reference being had therein to the accom-

10 panying drawing.

This invention relates to improvements in perforated combustion sections for blue flame stoves, of that type in which the combustion tubes are parallel, forming a com- 15 bined flame, and air and vapor mixing space between them.

This type of burner is well known to those skilled in the art, and in which the vapor is generated from a wick or trough 20 between the two perforated tubes of the section and at their lower ends, air passing into this space through openings formed in the two tubes and mixes with the vapor to support combustion, the combustion and mixing 25 continuing throughout the space between the tubes, and finally issuing from between their upper ends in a blue smokeless flame.

One object of my present invention is to provide an improved way of limiting the 30 amount of air passing through the upper end of the inner combustion tube into the space between the two tubes.

Another object of my present invention is to have the air restricting means perform 35 the double functions of restricting the air and lengthening the life of the inner tube by preventing the intense heat from warping the tube and burning it out.

A further object of my present invention 40 is to provide the outer combustion tube with an air restricting member located between its ends and just below the air restricting member of the inner tube, whereby the two tubes are kept cooler by having the heavy 45 combustion at the lower portion of the inner tube, and then shifting it to the upper portion of the outer tube, the restricting member of the outer tube serving to lengthen the life of the outer tube by preventing it 50 from warping and burning out as quickly as it otherwise does.

In the accompanying drawings—

Figure 1 is a vertical longitudinal sec- 55 tional view through a perforated combustion section embodying my invention.

Fig. 2 is an enlarged side view of a part 60 of one of the combustion sections, showing in exaggeration the large openings in the tube and the small openings in the air re- stricting member.

It is well known to those skilled in this art, that in the type of burner to which my improved combustion section is applied, vapor is generated between the outer tube 1 and the inner tube 2 of the combustion sec- 65 tion, and that the vapor is generated either from a wick or trough. As the vapor passes up between the two tubes, air passes in through the large perforations 3 of the outer tube and the large perforations 4 of the inner tube and mixes with the vapor. The air mingles with the vapor and maintains 70 the combustion, and this mingling and combustion continue throughout the space be- 75 tween the tubes, finally issuing between their upper ends in a smokeless blue flame.

In this type of combustion section, it has been found necessary to restrict the amount 80 of air passing between the tubes beginning a short distance above the lower ends of the tubes. This has been done in some instances by reducing the number and size of the openings in the inner tube, as shown in my 85 Patent No. 576,229 of February 2nd, 1897, or by perforated diaphragms located within the inner tube, of which an illustration is found in the Patent No. 607,641, July 19th, 1898, granted to A. J. Blackford.

The best results have been found to re- 90 quire a relative maximum amount of air through both the inner and outer tubes at their lower ends, and from that point up a relatively restricted amount of air supplied between the two tubes. This, as above 95 stated, has been accomplished by either dia- phragms alone, as in the Blackford patent, or by reducing the number of openings in the inner tube, as in the Ruppel patent re- ferred to, or by combining the perforated diaphragm and the reduced size of the open- 100 ings, as in my Patent No. 616,425, of De- cember 20th, 1898.

In these prior constructions of combustion sections, they are single wall tubes and have been relatively short lived by reason of overheating, causing a warping and burning out of the tubes.

The principal object of my present improvement is to lengthen the life of the combustion section, and this is done in my present improvement in two ways:

10 First, by shifting the heavy combustion from the intermediate portion of the outer tube to the corresponding portion of the inner tube, and then shifting the heavy combustion from the upper part of the 15 inner tube to the upper part of the outer tube, by first causing less air to pass through the intermediate portion of the outer tube than passes through the corresponding portion of the inner tube, and second, by 20 having less air pass through the upper portion of the inner tube than passes through the corresponding portion of the outer tube.

Second, by having the restricting member in the form of an auxiliary wall applied to the proper parts of the device, the auxiliary wall having openings registering with, but smaller than the openings in the wall of the tube. This gives additional thickness to the wall of the tube where it 25 is applied, affording greater strength to prevent warping of the tube and to prevent it 30 from becoming so intensely hot.

My improvement consists in having the auxiliary wall 4 applied to the outer tube 35 1, and provided with openings 5, which register with, but are smaller than the openings 3 of the outer tube, thus restricting the amount of air passing into the combustion and mixing space A, between the two tubes 40 throughout the length of the auxiliary wall. This wall is attached to the tube 1 in any desired manner, but, preferably, by the well-known method of electric spot welding.

My improved air restricting auxiliary 45 wall 6, is applied to the inner tube 2, and with its lower end 7 preferably beginning at or approximately in a horizontal line with the upper end of the auxiliary perforated wall 4 of the outer tube and extending to 50 the top of the inner tube. This auxiliary wall 6 is provided with air openings 8, which register with but are smaller than the openings 4 of the inner tube, and it too is attached to the inner tube preferably by 55 electric spot welding.

With this arrangement of auxiliary walls, the maximum amount of air passes to the flame space A at the lower ends of the combustion tubes where it is needed. At this 60 point the combustion for both tubes is substantially equal. The auxiliary wall 4 cuts down the amount of air passing into the flame space by having the smaller openings 5, and so far as the air supply is concerned, 65 it performs the function of the lower dia-

phragms in the Blackford and Ruppel patents referred to, but having the additional function of shifting the heavy combustion to the inner tube at that point.

The auxiliary wall 6 of the inner tube 70 performs a like function and shifts the heavy combustion to the outer tube.

Attention is called to the fact that the auxiliary walls 4 and 6 are considerably thinner than the wall of the inner and outer 75 tubes to which they are applied. The reason for this is two-fold, one being to prevent a heavy wall which would be objectionable, and the other being that it is not practical to punch small holes in a sheet as heavy 80 as that of which the inner and outer tubes are composed.

While I have shown and prefer to have the restricting auxiliary walls 4 and 6 on the inner sides of the inner and outer tubes, 85 I desire it to be understood that the auxiliary walls may be placed on the outer sides of the tubes.

Having thus described my invention, what I claim and desire to secure by Letters Pat- 90 ent is:—

1. A combustion section comprising parallel inner and outer perforated tubes, the inner tube having an auxiliary perforated wall tightly fitting it and having perforations registering with but smaller than the 95 perforations of the tube, for the purpose described.

2. An improved combustion section comprising parallel inner and outer perforated 100 tubes, the inner tube having an auxiliary wall tightly fitting its upper end and having openings registering with but smaller than the openings of the tube, for the purpose described.

3. An improved combustion section, comprising inner and outer parallel perforated tubes, the inner tube having an auxiliary wall tightly fitting the inner side of its upper end and having openings registering 110 with but smaller than the openings of the tube, for the purpose described.

4. A combustion section comprising inner and outer parallel perforated tubes, the inner tube having an auxiliary wall applied 115 thereto and having openings registering with but smaller than the openings of the tube, and the outer perforated tube having an auxiliary wall applied thereto and having openings registering with but smaller 120 than the openings of the tube, the auxiliary wall of the outer tube located below the auxiliary wall of the inner tube.

5. An improved combustion section comprising inner and outer perforated parallel 125 tubes, the inner tube having an auxiliary wall applied thereto and provided with openings registering with but smaller than the openings of the tube, the outer tube having an auxiliary wall applied thereto 130

below the auxiliary wall of the inner tube and having openings registering with but smaller than the openings of the outer tube and its lower end located above the lower 5 ends of the two tubes, the parts combined for the purpose described.

6. An improved combustion section comprising inner and outer perforated parallel tubes, said tubes having longitudinally extending air restricting members located in different horizontal planes with the lower end of the lowest restricting member located above the lower ends of the tubes, whereby the lower ends of both tubes are subjected 10 to substantially uniform combustion and the combustion thereabove shifted from one tube to the other, for the purpose described.

7. An improved combustion section comprising inner and outer perforated parallel 20 tubes, the outer tube having a longitudinal air restricting member for shifting the heavy combustion to the inner tube, and the inner tube having a longitudinally extending air restricting member above the air 25 restrictive member of the outer tube, whereby the heavy combustion is shifted to the upper end of the outer tube for the purpose described.

8. An improved combustion section of the type described, comprising parallel inner 30 and outer perforated tubes, the inner tube having relatively smaller perforations at its upper portion than at its lower portion, and the outer tube having air-passages at its upper portion larger than the small air- 35 passages of the inner tube, and the outer tube having also relatively small air-passages below its large air-passages and in a horizontal plane with the large air-passages of the lower portion of the inner tube, for 40 the purpose described.

9. An improved combustion section, comprising inner and outer parallel perforated tubes, the inner tube having at its upper end a longitudinally extending air restrict- 45 ing member, and the outer tube having a longitudinally extending air-restricting member having its lower end above the lower end of the tube and its upper end approximately in a horizontal line with the 50 lower end of the air-restricting element of the inner tube, for the purpose described.

In testimony whereof I hereunto affix my signature.

HENRY RUPPEL.
